COUPLER OPERATING MECHANISM

Willard F. Richards, Depew, N. Y., assignor to
The Gould Coupler Company, New York, N. Y.,
a corporation of Maryland

Application April 2, 1931, Serial No. 527,262

6 Claims. (Cl. 213—171)

This invention relates to coupler operating mechanism, and more particularly to such involving a self-locking operating rod.

The principal object of my invention, generally considered, is to provide coupler operating mechanism particularly adapted for actuating the rocker shaft operated lock in an automatic railway vehicle coupler and comprising a transversely extending rod or shaft, provided with an operating handle, supported adjacent said handle in a yoke which, in turn, is preferably pivotally mounted on a bracket connected to the end of a car, said yoke and rod being so formed that when the rod is in normal position, it is prevented from unlocking movement.

Another object of my invention is to provide an operating or uncoupling rod for a railway vehicle automatic coupler, and means for supporting the outer end of said rod, said means comprising a yoke pivotally mounted in a bracket to permit longitudinal movement of the coupler without cramping the operating rod, said rod being preferably formed with the yoke-received portion flattened on a slight taper to prevent rocking of the depending handle or arm of said shaft, said flattened portion being received in a constricted portion of the receiving aperture in the yoke to prevent unlocking rotation thereof.

A further object of my invention is to provide means for supporting the outer end of the operating rod of a railway vehicle automatic coupler and permit longitudinal and sidewise movement of said coupler while preventing undesired unlocking rotative movement of said rod.

Other objects and advantages of the invention relating to the particular arrangement and construction of the various parts will become apparent as the description proceeds.

Referring to the drawings illustrating my invention, the scope whereof is defined by the appended claims:—

Figure 1 is an elevational view showing one form of my uncoupling or operating rod with its outer portion supported from a locking bracket and its inner end connected to the rocker shaft of an associated coupler, fragmentary portions of said coupler being illustrated.

Figure 2 is a transverse sectional view on the line 2—2 of Figure 1, looking in the direction of the arrows.

Figure 3 is a fragmentary plan of the supporting bracket and associated operating rod.

Figure 4 is a horizontal sectional view on the line 4—4 of Figure 2, looking in the direction of the arrows.

Figure 5 is a horizontal sectional view on the line 5—5 of Figure 2, looking in the direction of the arrows.

Figure 6 is a fragmentary view corresponding to Figure 2, but showing a modification.

Figure 7 is a view corresponding to Figure 1, but showing a further modification.

Figure 8 is a transverse sectional view on the line 8—8 of Figure 7, looking in the direction of the arrows.

Figure 9 is a horizontal sectional view on the line 9—9 of Figure 8, looking in the direction of the arrows.

Referring to the drawings in detail, like parts being designated by like reference characters, and first considering the embodiment of my invention illustrated in Figures 1 to 5, inclusive, a railway vehicle automatic coupler operating mechanism is shown comprising an operating or uncoupling shaft 1 provided at its outer end with a depending handle portion 2, and at its inner end with a hook or connecting portion 3, normally articulately connected to an eye or outer portion 4 of a trunnion or operating shaft 5 of an automatic coupler 6. The coupler 6 is preferably of the type such as shown in the Kinne Patent No. 1,639,300, of August 16, 1927, or my application Serial No. 442,638, filed April 8, 1930, involving a lock operated by means of a link 7, the lower end of which is pivotally connected to a lifter arm or lever 8 actuated by the shaft 5, rotatable about its axis, upon rotation of the operating rod 1, although I do not wish to be limited to the use of my invention with this type of coupler.

The outer or manually operated end of the operating rod 1 is, in the embodiment shown, received in an aperture 9 in a yoke member 10, which member is, in turn, mounted for rotation about a vertical or upright axis in a bracket 11 adapted for connection to the end of a railway vehicle. For purpose of connection, the bracket 11 is preferably formed with a vertical web or base 12 apertured at 13 to receive connecting bolts or the like. The yoke 10 is desirably mounted in the bracket 11 by having a lower trunnion portion 14 received in a bearing or apertured portion 15 in a depending arm 16, the upper portion of said yoke being mounted between spaced flanges or webs 17 on the bracket and held in place by securing means, such as a rivet 18, extending loosely through an aperture 19 in the upper portion or web 20 of said yoke. The bracket 10 is desirably formed with a flange or web portion 21 overlying the upper end of the yoke extension 20.

On account of the loose mounting of the portion 20 of the yoke between the flanges 17 on the bracket, the outward tapering of said portion 20 and the fact that the rivet 18 is loosely received 5 in the aperture 19 in said portion 20, said yoke 10 is permitted to swivel to a limited extent about a vertical axis, thereby permitting longitudinal coupler movement without cramping of the operating rod 1 in the yoke 10.

10 In order to prevent undesired unlocking movement of the operating rod 1 as well as permit transverse movement or angling of the coupler, the portion 22 of the rod received in the aperture 9 of the yoke 10 adjacent said yoke preferably 15 has the sides thereof formed flat, as indicated at 23, and tapered or converged downwardly, as shown most clearly in Figure 2, the lower portion of the aperture 9 in the yoke being correspondingly formed so as to snugly receive said flattened 20 portion of the rod, while providing for clearance immediately upon even a slight raising movement of the rod, and thereby lock the same against rotation, and particularly unlocking or counter-clockwise rotation, as viewed in Figure 2, longitudinal movement of the rod with respect to the yoke being, of course, permitted for the length of the flattened portion, whereby the desired angling or swinging movement of the associated coupler is provided for.

30 Referring now to the embodiment of my invention illustrated in Figure 6, a yoke 10^a and associated operating rod 1^a are there disclosed which are identical with those of the preceding embodiment except that the restricted or lower portion 35 of the aperture 9^a in said yoke is formed with parallel sides rather than downwardly converging sides, and the flattened portion 22^a of the operating rod 1^a has parallel sides rather than downwardly converging sides, the slight clearance provided permitting the rod 1^a to slide freely 40 longitudinally and take the position shown by virtue of the normal inclination of the handle 2^a, as shown in dot-dash lines. As in the previous embodiment, the operating rod 1^a may be 45 unlocked for turning in the desired direction by raising the flattened portion 22^a above the constricted or lower portion of the aperture 9^a until it reaches the enlarged portion, which provides sufficient space for turning to the desired extent.

50 Referring now to the embodiment of my invention illustrated in Figures 7, 8 and 9, an arrangement is there disclosed involving an operating rod 1^b with a depending handle 2^b, the inner end 3^b of which is connected to the eye portion 4^b 55 of the operating trunnion or shaft 5^b of an automatic railway vehicle coupler 6^b. In the present embodiment, the hook portion 3^b is extended, as compared with the hook portion 3 of the previous embodiment, to avoid ready disconnection between the operating rod and eye of the shaft 5^b. The outer portion of said shaft 1^b, as in the previous embodiment, is flattened, as indicated at 60 22^b, and normally received in the constricted, preferably downwardly converging lower portion 65 of the aperture 9^b of the yoke 10^b. As in the previous embodiment, the yoke 10^b is pivotally mounted with respect to an associated supporting bracket 11^b, but in the present instance, the pivotal mounting is effected by having a partially 70 circular flange 20^b formed on the upper portion of the yoke 10^b, the bracket being grooved, as indicated at 21^b, to receive said flange and allow for pivotal motion in said bracket about a vertical axis. The upper portion of the bracket 10^b is also 75 desirably provided with a trunnion 14^b received in

a corresponding bearing or pocket 15^b on the bracket.

After assembly, which is effected by inserting the flanged portion 20^b in place beneath the bracket 11^b and rotating 90° to the position shown in Figures 7, 8, and 9, the yoke is preferably interlocked with respect to the bracket by means of a rivet or other retaining device 18^b engaging a cut-away portion 19^b in the flange 20^b of the yoke 10^b and permitting the desired amount of swivelling, while preventing movement to disengagement between the parts. Except as specifically described in connection with the present embodiment, the same may correspond with that of the first embodiment. The movement to unlocking 15 position, as in connection with the previous embodiments, is indicated by the arrow 24.

From the foregoing, it will be seen that I have provided an arrangement whereby the uncoupling or operating rod of a railway vehicle automatic coupler is self-locking and prevented from undesired rocking, which would ordinarily occur because of the swinging of the depending operating arm or handle upon stopping and starting of the associated railway vehicle. By virtue of 25 permitting pivotal motion of the supporting yoke, the coupler may move to a limited extent in and out, or swivel without binding of the operating rod in said yoke, the flattened portion of the operating rod extending the necessary distance on 30 either side of the normal position of the supporting yoke so as to permit the necessary longitudinal movement or free sliding of the operating rod upon sidewise angling or swivelling of the associated coupler. On account of self-locking provision for the coupler operating rod, the coupler is maintained in locked position, when desired, whereby the danger of creeping of the coupler lock, or possible total uncoupling when the coupler is subjected to train operating forces, is eliminated.

Although preferred embodiments of my invention have been illustrated, it will be understood that I do not wish to be limited except as specifically set forth in the appended claims, as my invention is applicable to all bell crank rods for top operated couplers as well as rocker shaft operated couplers.

I claim:—

1. A coupler operating mechanism comprising a 50 rotatable rod and means for supporting said rod, said means comprising a bracket adapted to be secured to a railway vehicle and a yoke mounted for rotation in said bracket about a normally vertical axis, said yoke having an aperture normally receiving said rod, the lower portion of said aperture being constricted and defined by upwardly diverging sides, said rod having a portion tapering in section in a corresponding manner and adapted to snugly fit in said constricted portion 55 of the aperture, the upper portion of said aperture being large enough to permit rotation of said rod.

2. In combination with a coupler having a rotatable lock-operating shaft, a rotatable operating rod articulated with respect to said shaft, and means for supporting the portion of said rod disposed away from said coupler to allow for coupler movement and prevent unintentional uncoupling, said means comprising a bracket secured to an 60 associated railway vehicle, and a yoke mounted for rotation in said bracket about an upright axis, said yoke being formed with an aperture the upper portion of which is adapted to rotatively receive the rod and the lower portion of which is 65 70 75

constructed and defined by upwardly diverging sides, said rod having a portion of tapering section, corresponding with the diverging sides, and adapted to snugly fit in said constricted portion to prevent uncoupling rotation of said rod.

3. In combination with an automatic coupler adapted to move longitudinally and swing from side to side with respect to an associated railway vehicle and having a lock-operating shaft rotatable about its axis, operating mechanism comprising a rod, means for supporting that portion of said rod disposed away from said coupler, said means comprising a bracket normally secured to said vehicle and a member supported by said bracket and adapted to rotate about an upright axis, said member having an aperture receiving said rod, the lower portion of said aperture having downwardly converging sides, and said rod having opposite sides flattened, converging to correspond, and cooperating with said constricted portion to prevent a substantial amount of rotation of said rod until raised out of engagement with the converging sides of said aperture, the flattened sides of said rod being extended both ways from the normal point of reception in said constricted portion and sufficient clearance being provided with respect to said constricted portion to allow free sliding of the rod through said aperture even when in lowermost position, and means connecting the shaft and the adjacent end of said rod while allowing free articulation therebetween, whereby desired movements of the coupler are permitted and binding of the rod in the supporting means prevented.

4. In combination with an automatic coupler adapted to move longitudinally with respect to an associated railway vehicle and having a lock-operating shaft rotatable about its axis, operating mechanism comprising a rod, means for supporting that portion of said rod disposed away from said coupler, said means comprising a bracket normally secured to said vehicle and a member supported by said bracket and adapted to rotate about an upright axis, said member having an aperture receiving said rod, the lower portion of said aperture being defined by upwardly diverging sides, and said rod having opposite sides flattened, upwardly diverging to correspond, and cooperating with the lower portion of said aperture to prevent a substantial amount of rotation of said rod until raised above said portion, and means connecting the shaft and the adjacent end of said rod while allowing

free articulation therebetween, whereby desired movements of the coupler are permitted and binding of the rod in the supporting means prevented.

5. A coupler operating mechanism comprising a rotatable rod and means for supporting said rod, said means comprising a bracket with upper and lower arms, and adapted to be secured to a railway vehicle, and a yoke with a lower trunnion portion pivotally mounted in the lower arm of said bracket and an upper elongated portion loosely confined between a bifurcated portion of the upper arm of the bracket, and means intersecting said bifurcated portions and elongated portion for limiting pivotal movement of said yoke, said yoke having an aperture normally receiving said rod, the lower portion of said aperture being constricted and defined by upwardly diverging sides, said rod having a portion, the sides of which diverge upwardly, and which is adapted to snugly fit in said constricted portion, the upper portion of said aperture being large enough to permit rotation of said rod when raised out of the constricted portion.

6. A coupler operating mechanism comprising a rotatable rod, and means for supporting said rod, said means comprising a bracket involving a normally upright web adapted to be secured to a railway vehicle, a generally horizontal lower web extending outwardly therefrom, and a yoke with upper flange portions received in grooved portions of said generally horizontal web, said yoke having an upper trunnion portion received in a downwardly opening pocket in said lower web, the upper portion of said yoke being narrow enough for insertion between the grooved portions in order to fit the upper trunnion in said pocket for pivotal mounting, said yoke being then turned approximately ninety degrees so that the flanges thereon guidingly fit in said grooves, and means intersecting said grooved portion and received in a notch in one of said flanges for limiting angling of said yoke, said yoke having an aperture normally receiving said rod, the lower portion of said aperture being constricted and defined by upwardly diverging sides, said rod having a portion the sides of which diverge upwardly, and which is adapted to snugly fit in said constricted portion, the upper portion of said aperture being large enough to permit rotation of said rod when raised out of said constricted portion.

WILLARD F. RICHARDS.
